[57] CLAIM

The ornamental design for a garden tool, as shown.

DESCRIPTION

FIG. 1—is a perspective view of the garden tool, showing my new design;

FIG. 2—is a left side elevational view thereof, with the opposite side being a mirror image;

FIG. 3—is a top plan view thereof;

FIG. 4—is a front elevational view thereof;

FIG. 5—is a bottom plan view thereof; and,

FIG. 6—is a rear elevational view thereof.

The handle is shown broken away in the above figures, to indicate indeterminate length.
